UNITED STATES PATENT OFFICE

91,816

DESIGN FOR AN ELECTRIC SEWING MACHINE

Herbert J. Goosman, Elizabeth, N. J., assignor to
The Singer Manufacturing Company, Eliza-
beth, N. J., a corporation of New Jersey

Application January 25, 1934, Serial No. 50,502

Term of patent 14 years

To all whom it may concern:

Be it known that I, HERBERT J. GOOSMAN, a citizen of the United States, residing at Elizabeth, in the county of Union and State of New Jersey, have invented a new, original, and ornamental Design for an Electric Sewing Machine, of which the following is a specification, reference being had to the accompanying drawing, forming a part thereof.

Figures 1 and 2 are perspective views of an electric sewing machine showing my new design; the parts shown in dotted lines being conventional.

I claim:

The ornamental design for an electric sewing machine, as shown and described.

In testimony whereof I have signed my name to this specification.

HERBERT J. GOOSMAN
